UNITED STATES PATENT OFFICE.

FREDERICK Y. DAWSON, OF WASHINGTON, DISTRICT OF COLUMBIA.

WEATHER-STRIP.

No. 815,941.

Specification of Letters Patent.

Patented March 27, 1906.

Application filed April 6, 1905. Serial No. 254,100.

To all whom it may concern:

Be it known that I, FREDERICK Y. DAWSON, a citizen of the United States, residing at Washington, District of Columbia, have 5 invented certain new and useful Improvements in Weather-Strips, of which the following is a specification.

The invention relates to improvements in weather-strips, and to the class of packing 10 weather-strips.

The object of the invention is to provide a simple, cheap, durable, and efficient strip of this character.

Heretofore weather-strips have been made 15 with a flat base and a rib which enters a groove in the sash; but this has been found inefficient, for the reason that when the sash and window-frame swell in damp weather the rib of the strip enters and impinges on the bottom of the groove, or if the rib is made short enough to allow for expansion of the sash then it binds against the base of the strip and causes considerable inconvenience. Furthermore, air and dust are liable to get past 20 the strips when the sash and frame shrink away from each other. These objections are overcome in the present invention, wherein the strip is formed with a yielding base, which at all times engages the edge of the 25 sash, and an upstanding rib, which when the sash is brought to bear on it impinges the groove at two points, thereby insuring an air-tight and dust-proof window.

In the accompanying drawings is shown 30 several forms of the invention, in which—

Figure 1 is a section through a part of the sash and sill, showing the strip applied, but not in operative engagement. Fig. 2 is a section through a part of the sash and sill, showing the strip in operative engagement. Fig. 3 is a section through a part of the sash and frame, showing the strip in operative engagement. Fig. 4 is an enlarged perspective view of the form of strip shown in Figs. 1, 2, and 3. 35 Figs. 5, 6, and 7 are perspective views of parts of the strip embracing modifications of the invention.

In the drawings, 1 represents the sash, and 40 2 the frame, the former being grooved at 8 to 50 receive the rib of the strip in the usual manner.

The strip is formed of a flat strip of sheet metal bent longitudinally to form a rib having parallel strips 4, the upper portion of 55 the rib being bent into a bead 3. It will be understood that the bead 3 may be dispensed

with and a plane rib 4' may be used, as seen in Figs. 7 and 6. The strip is then inclined or flared downwardly and outwardly from the rib or web, as at 6 6. Horizontal portions 5 5' are then formed, which lie in the same general plane with each other. These inclined portions 6 6, together with the horizontal portions, form the base of the strip. Perforations 9 are formed in the horizontal portions to admit of the strip being nailed to the frame. One side of the base is made wider than the other, which wide side 10 has the perforations 9, and is secured to the frame, leaving the other side 11 free to move 70 on the face of the frame.

When the strip is applied to the vertical portions of the frame, it will assume and maintain approximately the relation shown in Fig. 3. It will be seen that when the sash shrinks in dry weather, the inclined portions 6 6 of the base being of the nature of a spring will follow the sash, keeping in close relation thereto, thus forming a close joint and excluding all air or dust that might seek to enter. Furthermore, the rib will assume a position (shown in Fig. 3) touching the groove at two points. Should any air or dust pass the point 12, it would be checked at the point 13.

The strip as applied to the lower rail of the lower sash and the upper rail of the upper sash would upon the sash being moved away from the strip assume the position as shown in Fig. 1, but upon the sash being 90 brought to bear upon the strip would engage with the inclined portions 6 6 of the base and force same to an approximately horizontal position, causing the free side 5' of the base to slide outward and inclining the rib 4, so as 95 to touch the groove at 13 and 14, as best seen in Fig. 2.

In Fig. 5 it will be seen that one side of the base may be dispensed with.

From the foregoing it will readily be seen 100 that a very efficient weather-strip is made which insures a perfectly air-tight and dust-proof window.

Further modifications or minor changes may be made without departing from the 105 scope or principle of the invention.

Having thus described my invention, what I claim, and desire to secure by Letters Patent, is—

1. In combination with a frame and a 110 grooved sliding sash, a weather-strip comprising a horizontal member provided with

securing means, an inclined spring member, a groove-closing portion consisting of parallel spaced walls connected by a curved portion, one of said walls being connected to said inclined spring member, and the other being free, the whole of said groove-closing portion capable of lateral movement when pressure is exerted on the spring-inclined member.

2. A weather-strip having a horizontal member provided with securing means, an inclined spring member, a groove-closing portion consisting of parallel spaced walls connected by a curved portion, one of said walls being connected with said spring-inclined member and the other being free.

3. A weather-strip having a horizontal member provided with securing means, an inclined spring member, a groove-closing portion consisting of parallel spaced walls connected by a curved portion, one of said walls being connected to said spring-inclined member and the other being free and provided with an inclined spring portion.

In testimony whereof I affix my signature in presence of two witnesses.

FREDERICK Y. DAWSON.
